MAX HEINRICH, OF BERLIN-PANKOW, GERMANY, ASSIGNEE TO FIRM GRAF UND CO.
VERPACKUNGS-MASCHINEN, OF BERLIN, GERMANY

REISSUED

PHOTOGRAPHIC PRINTING PAPER

Application filed July 10, 1931, Serial No. 549,866, and in Germany July 12, 1930.

This invention relates to a photographic printing paper, especially for making copies of drawings, and consists essentially in providing possibilities for making drawings or photographic prints by means of a metal foil backing fastened on the rear of the original drawing and by means of a sheet of copying paper fixed to the outer surface of said backing. A further modified form of paper according to my present invention consists therein that said backing is composed of a plurality of foils which are connected with each other along wave-shaped edges.

15 The photographic printing paper forming part of my present invention relates in general to that class of copying papers which serve for making drawings in the form of photographic prints which are drawn to scale for use in factories or shops as a template or marking drawing for making a work-piece therefrom.

In the accompanying drawing I have shown an example of my new photographic paper for making drawings or photographic prints according to my present invention, Fig. 1 being a section showing the several layers of which the new paper is composed, Fig. 2 a top-view on Fig. 1 showing in particular the paper according to Fig. 1 with a drawing of a work piece thereon and Fig. 3 a longitudinal section through Fig. 2.

35 The new photographic printing paper which forms part of my present invention consists of the sheet *d* which is the drawing sheet proper, a backing consisting of metal foils *a* and *b* applied to said sheet *d* by a process of hard rolling, and the light-sensitive layer *c*. The sheet *d* may be fastened to the backing *a* and *b* by means of a paste or applied thereto in liquid condition.

More particularly, the drawing sheet *d* serves for protecting the backing *a* and *b* which consists of aluminum against decomposing if the photographic print is developed by means of an acid or salt. Drawings may be made on the drawing sheet or protective layer *d* no matter of what kind the latter may be by means of pencil or drawing ink and

also erasures may be made on said drawing sheet.

As aluminum at a thickness of about 0.04 mm. can only be rolled in widths of from 50-60 cm. it would be impossible to make photographic printing papers of the present kind of a width exceeding these dimensions. In order to permit the making of photographic printing papers of a greater width than about 50-60 cm., I further propose to make up the aforementioned backing of a plurality of sheets *a* and *b* of metal foil and to make the abutting edges of said sheets *a* and *b* of wave-shaped or dovetail conformation, as shown at *f*, *f* in Fig. 2. The wave-shaped edges along which the metal sheets or layers *a* and *b* abut as shown in Figs. 1, 2 and 3 are possessed of the great advantage that they permit to make copies of drawings of any desired width by placing a plurality of such metal sheets or layers having a limited width side by side with their wave-shaped edges abutting, thereby rendering it possible to make drawing templates for work-pieces of any desired size. The form of the wave-shaped edges *f* may be somewhat different from that shown in the drawing. More particularly, said wave-shaped edges *f* may be of the form of sine-curves of any desired amplitude, that is said edges are not necessarily of the specific shape of serpentine lines as shown in Fig. 2 of the drawing. When using edges *f* of the form of a sine or similar curve, the curve may also be more flattened or more pointed. The wave-shaped edges *f* furthermore serve to prevent perforation of the paper when making a drawing thereon or to prevent breaking during being folded, such breaking being liable to occur in case sheets are used which abut with each other along straight edges.

Connecting the two sheets *a* and *b* along wave-shaped edges, as compared with overlapping edges, is possessed of the advantage that the drawing surface proper will be fully plane. The lines of the drawing, evidently will intersect the edges which abut with each other along any kind of wave-shaped lines only at points, while in case of straight edges or overlapping edges the lines of the draw-

ing will intersect the abutting parts of the two sheets along a greater or even the entire length which may eventually result in tearing up the backing *a, b.*

5 The novel effect which may be attained by my present invention may be clearly seen from Fig. 2. In Fig. 2 *g* designates the drawing of an angle-iron with holes, *h*, *h*₁,
10 *h*₂, *h*₃ and *h*₄ are the imaginary points of intersection between the wave-shaped edges *f* of the metal foils and the border lines of said angle-iron. It will be seen that the angles of the intersection between said border
15 lines and said wave-shaped edges are all very nearly right angles, with the result that dur-

ing the process of copying the drawing can-
not be distorted by warping or the like.

I claim:

As an article of manufacture, a photo-
graphic printing paper, especially for mak- 70
ing copies of drawings, said paper consisting
of a light-sensitive sheet, a metal foil back-
ing fastened to the rear surface of said light
sensitive sheet, said metal foil backing being
75 composed of several pieces placed side by
side and abutting with each other along
wave-shaped edges, and a sheet of drawing
paper fastened to the rear surface of said
metal foil backing.

In testimony whereof I affix my signature. 80
MAX HEINRICH.
